(57) **CLAIM**

The ornamental design for an incision nerve protector as shown and described.

DESCRIPTION

FIG. 1 is a front perspective view of an incision nerve protector.

FIG. 2 is a rear perspective view of the incision nerve protector of FIG. 1.

FIG. 3 is a top view of the incision nerve protector of FIG. 1, wherein the bottom view of the incision nerve protector of FIG. 1 is identical to the top view.

FIG. 4 is a front view of the incision nerve protector of FIG. 1.

FIG. 5 is a rear view of the incision nerve protector of FIG. 1.

FIG. 6 is a side view of the incision nerve protector of FIG. 1, wherein the opposite side view of the incision nerve protector of FIG. 1 is identical; and,

FIG. 7 is a perspective view of the incision nerve protector of FIG. 1 shown in an installed environment.

All broken lines represent subject matter, structure, and/or features that form no part of the claimed design. More specifically, the broken lines shown within the shaded areas illustrate portions of the incision nerve protector that form no part of the claimed design; the broken lines showing an optional attachment strap in FIG. 7 illustrate portions of the incision nerve protector that form no part of the claimed design; and the broken lines in FIG. 7 showing the human form illustrate environment and form no part of the claimed design.

1 Claim, 6 Drawing Sheets
